(57) **CLAIM**

The ornamental design for a display screen or portion thereof with graphical user interface, as shown and described.

DESCRIPTION

FIG. 1 is a front view of a display screen or portion thereof with graphical user interface showing the new design in

accordance with a first embodiment, wherein the display screen is flat except that it is curved on the right side; FIG. 2 is a front view of a second embodiment thereof; FIG. 3 is a front view of a display screen or portion thereof with graphical user interface showing the new design in accordance with a third embodiment, wherein the display screen is flat except that it is curved on the left side; FIG. 4 is a front view of a fourth embodiment thereof; FIG. 5 is a right-side view of the image shown in FIG. 1; FIG. 6 is a right-side view of the image shown in FIG. 2; FIG. 7 is a left-side view of the image shown in FIG. 3; FIG. 8 is a left-side view of the image shown in FIG. 4; FIG. 9 is the image shown in FIG. 1, with broken lines showing a mobile phone to illustrate environment; FIG. 10 is the image shown in FIG. 2, with broken lines showing a mobile phone to illustrate environment; FIG. 11 is the image shown in FIG. 3, with broken lines showing a mobile phone to illustrate environment; FIG. 12 is the image shown in FIG. 4, with broken lines showing a mobile phone to illustrate environment; FIG. 13 is the right side image shown in FIG. 5, with broken lines showing a mobile phone to illustrate environment; FIG. 14 is the right side image shown in FIG. 6, with broken lines showing a mobile phone to illustrate environment; FIG. 15 is the left side image shown in FIG. 7, with broken lines showing a mobile phone to illustrate environment; FIG. 16 is the left side image shown in FIG. 8, with broken lines showing a mobile phone to illustrate environment; FIG. 17 is a rear view of the images shown in FIGS. 9, 10, 13, and 14; FIG. 18 is a left-side view of the images shown in FIGS. 9, 10, 13, and 14; FIG. 19 is a top view of the images shown in FIGS. 9, 10, 13, and 14; FIG. 20 is a bottom view of the images shown in FIGS. 9, 10, 13, and 14; FIG. 21 is a rear view of the images shown in FIGS. 11, 12, 15, and 16; FIG. 22 is a right-side view of the images shown in FIGS. 11, 12, 15, and 16; FIG. 23 is a top view of the images shown in FIGS. 11, 12, 15, and 16; and, FIG. 24 is a bottom view of the images shown in FIGS. 11, 12, 15, and 16.

(Continued)

The broken lines in FIGS. 1-16 showing portions of the display screen or portion thereof with graphical user interface form no part of the claimed design. The broken lines in FIGS. 9-24 showing the mobile phone are included for the purpose of illustrating environment structure and form no part of the claimed design.
